GEAR HOUSING FOR AUGER

John Henry Danuser, 1/2 Danuser Machine Co.,
Fulton, Mo. 65251

Filed Oct. 3, 1966, Ser. No. 4,118

Term of patent 14 years

(Cl. D55—1)

FIG. 1

FIG. 2

FIG. 3

FIG. 4

FIG. 5

FIG. 6

FIG. 1 is a front elevational view of my new design for a gear housing for auger, the auger being illustrated in broken lines for illustrative purposes only;

FIG. 2 is a side elevational view thereof;

FIG. 3 is a bottom plan view thereof;

FIG. 4 is a top plan view thereof;

FIG. 5 is a rear elevational view thereof, and

FIG. 6 is an elevational view of the side opposite to FIG. 2.

I claim:

The ornamental design for a gear housing for auger, substantially as shown and described.
